BYRON E. ELDRED, OF BRONXVILLE, NEW YORK, ASSIGNOR TO COMBUSTION UTILITIES COMPANY, OF NEW YORK, N. Y., A CORPORATION OF NEW YORK.

PROCESS OF OPERATING GAS-PRODUCERS.

No. 813,628.

Specification of Letters Patent.

Patented Feb. 27, 1906.

Application filed August 10, 1905. Serial No. 273,668.

To all whom it may concern:

Be it known that I, BYRON E. ELDRED, a citizen of the United States, and a resident of Bronxville, in the county of Westchester and State of New York, have invented certain new and useful Improvements in Processes of Operating Gas-Producers, of which the following is a specification.

This invention relates to process for the regulation and control of the temperature of combustion in the production of fuel or power gas by the producer process.

It relates particularly to process for the utilization of endothermically-reacting fixed gases for the chemical or endothermic retardation of combustion, whereby the gas-producing fuel mass is cooled to or maintained at a temperature most effective for the gasification of the particular fuel employed. Especially useful for such endothermic cooling of a fuel-bed is the fixed gas carbon dioxide, derived conveniently from waste products of combustion and from various calcining operations, such as lime or cement burning, glass manufacture, and the like. Its proper application to the fuel-bed to completely utilize all of its endothermic virtues has, however, up to the present time been a problem difficult of solution. The varying nature of products of combustion must needs call for a method of utilization of great flexibility or latitude of operation. Regulation and control of the gasifying fire is the *sine qua non* of successful producer practice. No two furnaces or kilns yield products of combustion of like composition. The stack-gases from an open-hearth steel furnace may, for example, contain six per cent. of carbon dioxide, from a regenerative gas-bench possibly eighteen per cent. of carbon dioxide, and from a limekiln often thirty-five per cent of carbon dioxide, whence it is evident that a process capable of using the waste gases from all of these furnaces must be conformable within wide limits.

Prior methods of using stack-gases in producer operation usually have involved as a part of the apparatus used for the purpose either a pump, fan-blower, or positive pressure-blower and the like, employing a mixture of stack-gas and air, or else they have involved an air or steam jet. With processes carried out with such apparatus as are enu-

merated in the former category serious explosions have been known to occur, owing to the backflow of the producer-gas into the blast-mains when the impelling force ceases, thereby giving rise to explosive mixtures which are subsequently ignited by an entraining flame from the producer-fire. The steam-jet labors under the disadvantage, so far as I am advised, of condensation difficulties which seriously impair its theoretical or alleged efficiency. The air-jet is unsuited for use with weak furnace-gases—that is, gases weak in carbon dioxide—because the quantity of air required for creating the necessary inductive force results in the dilution of the stack-gas and the introduction of so large a proportion of oxygen that the proper cooling of the fire to an effective gasifying point cannot be realized.

My process involves the use of a jet of the products of combustion themselves, thereby securing with stack-gases of all compositions a regulation or control of producer temperature manifestly impossible by the above-mentioned methods. My process consists in the injection of carbon dioxide or products of combustion into the producer-draft-passage in the form of an induction-jet, whereby a suction or inductive action in the direction of the fuel mass of the producer is created, and thereby additional products of combustion or air, or both, either cool or heated, are drawn into and form a part of the producer-draft. The carbon dioxide or products of combustion employed for the jet are preferably cooled and purified before use. Carbon dioxide introduced by inductive action need not be purified, although it may be cooled whenever proper regulation of the producer-fire demands draft-gases of low sensible heat.

In the accompanying diagrammatic drawing is shown a view in elevation of apparatus adapted to carry out my process.

In the drawing, 1 is a gas-producer having the fuel-hopper 2, the gas-outlet 3, the water seal 4, and the "injector" 5.

6 is a furnace from which by the conduit 7 products of combustion are passed into the purifier 8.

At 9 is shown a compressor connected on the inlet side to the purifier 8 by the pipe 10. In this pipe is situated an air-inlet 20, whereby a regulated amount of air may be drawn

in and mixed with the products of combustion, and the dampers 11 and 12. On the exhaust side of the compressor is connected the pipe 13, which terminates at the injector 5 in 5 the jet 14.

15 is a valve to control the flow of gas. From the furnace-stack another stack gas-passage 16 extends to the injector 5. This passage is also supplied with an air-inlet 17. 10 Dampers 18 and 19 regulate the flow of stack-gas and air, respectively.

My method of operation is as follows: A bed of ignited coal or other fuel is built up in the producer 1, and a blast containing carbon dioxid is introduced through the injector 5 by operating the compressor, whereby stack-gases are withdrawn from the furnace through 7, are scrubbed or purified in 8, and are forced into the blower at 14. The induction created by the so-formed jet serves to draw products of combustion and air, if necessary, through the passage 16. By varying the proportion of oxygen to carbon dioxid a mixture is soon formed which will maintain 25 the producer at an effective gasifying-point. It will be seen from the foregoing that my process permits of the independent regulation of each producer; that it avoids the use of large passages or conduits for handling and 30 injecting the producer-draft, thereby reducing the danger from explosions to a minimum; that it avoids the use of steam or other non-permanent gas as an impelling medium, and therefore incurs all the economies to be 35 expected from the use of a non-condensing gas; that it allows of the purification and cooling without condensation losses of the endothermic constituent used as a propelling means, and that it permits of the use of 40 stack-gas alone without additions of air when aforesaid stack-gas is very weak in carbon dioxid. The difficulties, therefore, which have harassed other investigators in this promising field have been eliminated by my

process, and all those benefits and economies 45 theoretically possible in the use of carbon dioxid become now practically possible through my controllable method for its utilization.

What I claim is—

1. The process of operating a gas-producer which consists in inducing and controlling a draft-current of commingled air and products of combustion into said gas-producer by means of an inductive jet of products of combustion. 50

2. The process of operating a gas-producer which consists in inducing and controlling a draft-current containing regulated proportions of air and of products of combustion by 60 means of a jet of air and products of combustion, and introducing said jet and entrained gaseous mixture into the producer.

3. The process of operating a gas-producer which consists in feeding into the same a 65 high-pressure jet of commingled air and products of combustion through an unsealed passage-way containing a similar mixture whereby the feed will be responsive to the pressure in the producer. 70

4. The process of operating a gas-producer which consists in cooling, purifying and compressing products of combustion, forming the compressed gas into an inductive jet and impelling therewith an additional portion of 75 products of combustion into a producer.

5. The process of operating a gas-producer which consists in employing an inductive jet of cooled and purified products of combustion to impel another portion of products of 80 combustion into a producer.

Signed at New York, in the county of New York and State of New York, this 4th day of August, A. D. 1905.

BYRON E. ELDRED.
